UNITED STATES PATENT OFFICE.

ANDREW J. BENTON, OF WASHINGTON, DISTRICT OF COLUMBIA, ASSIGNOR
TO LANSTON MONOTYPE MACHINE COMPANY, OF PHILADELPHIA, PENN-
SYLVANIA, A CORPORATION OF VIRGINIA.

GEAR-ADJUSTING MECHANISM.

No. 857,783.

Specification of Letters Patent.

Patented June 25, 1907.

Application filed November 14, 1905. Serial No. 287,291.

To all whom it may concern:

Be it known that I, ANDREW J. BENTON, a citizen of the United States, residing at the city of Washington, District of Columbia, have invented certain new and useful Improvements in Gear-Adjusting Mechanisms, of which the following is a specification.

This invention relates to gear-adjusting mechanisms, and more particularly to means for adjusting or manipulating the "unit-wheel" and related registering mechanisms of a Lanston monotype keyboard; and it consists, essentially, of means for adjusting or manipulating the unit-wheel when necessary to place said wheel and the related registering mechanisms in any desired position, the said means performing this function without other effort than releasing the unit-wheel pawl by depressing the "restoring-key" and then pressing upon and turning the thumb or finger piece in either direction.

The Lanston monotype keyboard is so constructed that the operator is enabled to make a "single justification," or to so perforate the paper film or record-strip as to cause a change in the size of the spaces to be cast, as many times as is desired in any one line, the length of said line being determined by striking first one and then two of the justifying-keys (called "double" justification), which causes the caster to trip onto the galley the completed line. The operation of making a justification carries the unit-wheel forward the number of teeth represented by the number of units registered by the justifying-keys struck. In matter where the operator desires to make one or more changes in the sizes of the spaces cast—as, for instance, in tabular matter containing a number of "reading" columns—the unit-wheel must in each instance be restored to the position which it occupied previous to being moved by the operation of justifying before the keyboard is operated to perforate the paper film or record-strip to produce the next column. The return of the unit-wheel to the desired position also automatically restores the em-scale pointer to a corresponding position and lowers the justifying-scale pointer to zero or non-indicating position. As at present manipulated, the operator grasps the unit-wheel between the thumb and forefinger of the left hand, depresses the restoring-key with the

fingers of the right hand, and then moves the unit-wheel the desired number of teeth in either direction.

The adjustment of the unit-wheel in the above-described manner involves, first, soiling the fingers by contact with the dirt and oil which invariably collects on movable mechanical parts; second, danger of bruising or lacerating the fingers, and, third, the attempts necessary for perfect adjustment of the unit-wheel by an inexperienced operator or one not required to make this adjustment frequently enough to maintain that digital skill necessary for instantaneous and perfect adjustment or whose hands by reason of coldness or nervousness are in the slightest degree unsteady. My invention removes all these objections and renders the manipulation of the unit-wheel both rapid and accurate.

Referring to the accompanying drawings, Figure 1 is a front elevation of one of the preferred forms of my invention arranged for engaging the unit-wheel of a Lanston monotype keyboard and showing in dotted lines the position assumed when in operative contact with said wheel, the portion to which it is attached and the justifying-scale pointer being also shown in dotted lines. Fig. 2 is a rear elevation of the device, illustrating one means of securing the sliding frame to the base-piece. Fig. 3 is a top plan view of the device, showing the top portion of a well-known form of clamp, the contour of the frame, and the extensions or projections for affording bearing for the gearing. Fig. 4 is a cross-section on the lines 4-4, Fig. 3, looking in the direction of the arrow.

Similar reference-numerals designate like parts in all the views.

1 is an attaching-clamp of well-known character, a projecting portion of which is bent at right angles for connection with the base-piece 2.

2 is the base-piece upon which the frame slides.

3 is the frame, which affords bearing for the rod or shaft 4 and slides on the base-piece 2.

4 is a rod or shaft connected to and operating gear 6.

5 is a thumb or finger piece for operating the rod or shaft 4.

6 is a bevel-gear connected with and driving gear 7 or other suitable mechanism.

7 is an auxiliary bevel-gear meshing with gear 6 and adapted for driving gear 8 or other suitable mechanism.

7', 7'', and 7''' are extensions of or projections from the frame 3 and affording bearings for gears 6, 7, and 8.

8 is an auxiliary gear fast on the shaft of gear 7.

9 is a spiral spring for holding the device in its normal or inoperative position.

I have illustrated and described gear 6 as a "bevel" gear for the purposes of the adjustable device shown, and I have also designated gears 7 and 8 as "auxiliary bevel gear" and "auxiliary gear," respectively, for the same reason. As described below, these gears 7 and 8 may be dispensed with without in any manner limiting my invention, and it is my desire to be not limited to the use of the type of gears 6, 7, and 8, the specific form of frame shown and described, nor the use of a sliding frame.

I have illustrated and described a sliding frame for the purpose of enabling the device to be maintained in an inoperative position, this being the most simple and convenient form for adjusting this device to mechanisms already in use. Where the device is to be constructed and maintained as an integral part of the mechanism to be operated it is preferable where the gearing to be contacted can withstand the slight additional friction that the gearing of my device be maintained in constant contact with the mechanism to be operated, thus eliminating the necessity for the spring or other means for maintaining the device out of operative contact and removing the necessity for a sliding or otherwise movable construction.

When intended for permanent attachment or constant contact with the gear to be operated, it is only necessary to utilize a single gear-wheel at one end of the operating rod or shaft. This gear-wheel would in this instance be in mesh with the teeth of the gear to be operated, or, more preferably, with a bevel or other gear attached to or cast integral with the gearing which it is intended to manipulate or control.

Without departing from the principle herein set forth, the device can be arranged to offset the gears in the opposite direction to the form shown and described for the purpose of extending from behind the justifying-scale pointer of a Lanston monotype key

board, the direction of application or slight changes in the form of my invention not affecting the integrity of the principles claimed by me. For instance, while I have illustrated and described one form of device and indicated other methods of construction and operation of devices for producing the same result, I do not desire to be limited to these specific forms, but to all mechanisms for adjusting or manipulating gearing which is operated or manipulated by the turning of a rod or shaft and the consequent adjustment of one or more gear-wheels with and the operation of other gear-wheels which are not operated by the regular operation of the mechanism to which it is applied.

When it is desired to adjust the units wheel finger piece 5 is grasped and pressed until auxiliary gear 8 enters the teeth of the units wheel, after which the restoring key is operated thereby withdrawing the holding pawl from the units wheel and releasing the latter so that it can be advanced or retracted the number of teeth desired by the rotation of thumb wheel 5. When the adjustment has been made the restoring key is released before pressure is taken off the thumb wheel, thereby retaining the parts in position until re-engaged by the holding pawl of the escapement devices.

Having thus fully described my invention, what I claim, and desire to secure by Letters Patent of the United States, is—

1. The combination with the units wheel of a monotype keyboard, of an adjusting device such as described including a gear wheel movable into and out of engagement with said units wheel and provided with actuating devices for controlling both the rotation and advance of said wheel.

2. In a monotype keyboard and in combination with the units wheel thereof, an adjusting device for said units wheel comprising a gear movable toward and from the units wheel, a supporting frame for said gear movable in bearings on the main frame, and an actuating shaft extending in the direction of motion of said supporting frame and coupled with said gear for reciprocating and rotating the latter.

In testimony whereof I affix my signature in presence of two witnesses.

ANDREW J. BENTON
